UNITED STATES PATENT OFFICE.

M. C. BURLEIGH, OF SOMERSWORTH, NEW HAMPSHIRE.

IMPROVEMENT IN MOLDING STOVE-GRIDDLES.

Specification forming part of Letters Patent No. 32,465, dated June 4, 1861.

To all whom it may concern:

Be it known that I, M. C. BURLEIGH, of Somersworth, in the county of Strafford and State of New Hampshire, have invented a new and useful Improvement in Molding Flat or Smooth Top Griddles for Cooking - Stoves; and I do hereby declare that the following is a full, clear, and exact description of the same, reference being had to the annexed drawings, making a part of this specification, in which—

Figure 1 is a vertical central section of a flask with the pattern fitted within it and provided with my invention. Fig. 2 is a plan or top view of the pattern. Fig. 3 is a plan or top view of the handle by which the griddle is lifted or moved. Fig. 4 is an underview of the same. Fig. 5 is a longitudinal section of the same.

Similar letters of reference indicate corresponding parts in the several figures.

This invention consists in providing the pattern with a tongue or an adjustable plate, substantially as hereinafter described, whereby the griddle may be cast without any core-boxes, wires, or chills, which is necessary in the ordinary plan of molding in order to form a means to connect the handle to the griddle for the purpose of moving the latter when required.

To enable those skilled in the art to fully understand and construct my invention, I will proceed to describe it.

A represents the pattern, which is made in the usual way, provided with a recess or sunken portion, *a*, to form a cavity in the casting to receive the end of the handle. This cavity may be of the usual form, but it is provided with a movable tongue, B, which constitutes the gist of the invention, as referred to in the recital of invention. This tongue is formed of a small strip of wood or metal, which is fitted in an oblique slot in the pattern, so as to project a certain distance within the re-

cess *a* of the pattern, as shown in Figs. 1 and 2. This tongue, when fitted in the pattern, is flush with its under surface *a'*, and the outer end of the tongue is flush or about flush with the face side *b'* of the pattern. The recess *a* has inclined sides, as shown in Fig. 1, and the recess is sufficiently large to receive the end of the handle C, which is provided with a recess, *c*, of such dimensions that it will receive the tongue B if the end of the handle be inserted in the recess *a*. The handle C is cast in the usual way, and is of the ordinary form.

The mold is formed as follows: The lower flask, D, is filled with sand, and the pattern A is bedded in the flask D, face side down, and the tongue B inserted in the pattern in the proper position. The upper flask, E, is then placed on the flask D and packed with sand, and is then removed, and the tongue B is withdrawn from the pattern and the pattern drawn from flask D. The flask E is then placed on D and the mold is completed, the recess formed in the sand by the tongue B causing a lip to be cast in the recess of the griddle for the end of the handle to fit under, and enabling the griddle to be lifted and moved by the handle.

Thus it will be seen that by the use of the tongue B the lip may be cast without any core-box, and all wires and chills dispensed with.

Having thus described my invention, what I claim as new, and desire to secure by Letters Patent, is—

The employment or use, with the pattern A, of the movable tongue B, substantially as described, fitted in the pattern and in such relation with its recess *a* as to admit of a lip being cast with the griddle, as and for the purpose herein set forth.

M. C. BURLEIGH.
